SEWING MACHINE

Mathias Pedersen, Brooklyn, N. Y., assignor to
 American Machine and Foundry Company, a
 corporation of New Jersey

Application July 13, 1940, Serial No. 345,352

14 Claims. (Cl. 112—171)

This invention relates to sewing machines and more particularly to improvements in sewing machines of the type using a double pointed needle having an eye located between the points, and means for projecting the needle with a thread back and forth through material to be sewed.

In machines of this type, which usually employ a relatively short thread, the length of which diminishes as each stitch is formed, due to the pulling of the thread through the material being sewed, it is advisable to provide some means for supporting the thread so that it will not become tangled or frayed excessively by and during the pulling operation. Accordingly, it is an object of my invention to provide improved mechanism for properly disposing the thread relative to the pulling device and the means which propel the needle back and forth through the material to be sewed.

It is a further object of my invention to provide improved thread disposing mechanism which may include a drum acting as a receiving surface for thread being pulled through material by a thread puller, and furnish the drum with a series of slots for guiding the free end of the thread into mechanism for properly positioning the thread relative to the thread puller and needle.

It is an additional object of my invention to provide an improved thread receiving drum preferably located adjacent the thread puller and form in a part of the drum proximate the path of travel of the puller a series of slots which direct the thread into further thread guiding mechanism for the formation of proper stitches.

Due to the fact that during the pulling of the thread in the formation of stitches, the tip of the free end often becomes somewhat frayed with the result that some difficulty may be experienced in directing the thread into the guiding means used for disposing the thread in proper relationship to the thread operating instrumentalities of the machine. Accordingly, my invention also consists in the provision of a thread receiving surface, such as a stationary drum, about which thread is disposed by a thread puller and a ledge forming a part thereof or associated therewith together with slots formed in a part of the surface of the drum for directing the thread downwardly off the ledge portion of the drum, and thereby substantially eliminate improper thread disposition, such as locking of thread lengths on the ledge of the drum, especially in instances where the end of the thread becomes frayed and tends to prevent movement of the thread from the ledge.

My invention further consists in the provision

5 of a guide plate provided with a substantially L-shaped slot, the opening end of which is located adjacent the thread guide ledge of the drum mechanism, which acts as a guide in disposing the thread with respect to the thread puller and needle.

It is an added object of my invention to provide thread guiding means associated with the stationary drum mechanism about which thread is disposed by the thread puller and slots in a portion of the drum mechanism for directing the free end of the thread downwardly onto the thread receiving ledge of the drum for lateral guiding during the stitching operation.

15 With these and other objects not specifically mentioned in view, the invention consists in certain combinations and constructions which will be hereinafter fully described, and then set forth in the claims hereunto appended.

20 In the accompanying drawing, which forms a part of this specification, and wherein the several reference characters designate the same or like elements:

Figure 1 is a partial front view of the improved 25 thread receiving drum of my invention;

Figure 2 is a partial end view taken on line 2—2 of Figure 1 showing the cam actuated braking mechanism and its relation to the thread guiding and supporting mechanism;

30 Figure 3 is an enlarged detail view of a portion of the drum mechanism taken on line 3—3 of Figure 1;

Figure 4 is a detail view taken on line 4—4 of Figure 1 showing a part of the drum which is provided with a series of cut-out portions;

35 Figure 5 is a detail view showing the thread puller engaging the front loop of the thread; and

Figure 6 is a partial side view partly in section showing a detail of the thread guiding drum.

40 Referring to the drawings, Figure 1 shows a thread puller 202 which may be similar in construction and operation as shown in co-pending application, Serial No. 289,907, filed August 12, 1939, by C. W. Johnson, for Sewing machine,

45 which has matured into Patent No. 2,368,066, granted January 23, 1945. According to the disclosure in said application, thread puller 202 is mounted on an arm 246 fast to a shaft 245 which is driven by suitable means not forming a part of this invention to translate the puller 202 clockwise to pull the loose end of the thread through the material and form stitches therein. As the puller 202 travels in a clockwise direction, the front of the loop of thread, which has been formed 50 by the movement of the needle 81 upwardly

towards the work, as described in the above referred to application, is caused to move along the tapered portion 301 (Figure 5), of the puller which directs the thread into a groove 302 of the puller whereby the free end of the thread is pulled through the material being sewed as the arm continues its rotary movement in a clockwise direction, as shown by the arrow in Figure 1. Puller 202 is provided on its under face with a groove, the purpose of which will be described herein-after.

The rotation of the arm 246 and the operation of puller 202 causes the thread to be guided onto a flange or ledge 307 of a stationary drum member 308 which is fixed to stationary drum member 309 to form the assembled drum structure 224, as seen in Figures 1, 2, 3 and 4. As shown, drum member 309 is a substantially L-shaped cylindrical member having a substantially vertical circumferential flange and a lateral circumferential flange 310a provided with a thread receiving surface, and a tapered thread guiding face 307a. A guide member 306, which is provided with a thread trap 311, assists in guiding the thread along face 307a onto flange or ledge 307. Groove 202a formed in thread puller 202 is complementary with guide 306 and in the movement of the thread puller 202, assists in positively directing the thread downwardly onto flange or ledge 307 due to the cooperation between the groove 202a and the guide 306 which insures that the thread cannot wander laterally but must be directed downwardly onto the flange or ledge 307. As the puller 202 travels it also positions a part of the thread B in a groove 310 formed in the lateral circumferential flange of member 309 and as its movement continues it pulls the free end F of the thread completely through the work, at which time thread gripping arms 200 and 201, which hold the fixed end of the thread against tension, open and permit the lower needle bar to ascend in a manner similar to that set forth in the above referred to application.

At substantially the same time clamping jaws 288 and 289, which have engaged the thread as described in said application, swing upwardly and laterally in unison with the ascent of the needle bar 64, and in so doing, thread A is caused to enter a trap 311 and is thereby disposed out of the path of the thread puller. The ascent of the jaws 288 and 289 causes the thread A to be moved from flange or ledge 307 (Figure 3) into the space between a finger or transverse thread guide 312, and the lateral circumferential flange 310a of drum 309. As shown in Figures 1 and 3, thread guide 312 constitutes a laterally projecting extension of member 313 secured to drum 309. Thread guide 312 coacts with inclined face 309a formed on the lower portion of the lateral circumferential flange 310a of drum 309 in guiding the thread into a guide slot 314 provided in the vertical flange or wall of the member 309 for holding the thread out of the path of puller 202. The slot 314 is formed in the vertical flange of member 309 a sufficient height to allow the thread F to extend from needle 81 without much sag. When needle 81 has been gripped by the upper needle bar 63, the latter ascends its full stroke, descends slightly, forming a loop in the thread and dwells. Shortly before the ascent of the needle, jaws 288 and 289 are opened by cam lever 282 (Figure 2) so that the needle may draw some of the thread through the work from slot 314. The gripper (Figure 2) consists of a

jaw 288 slidably supported on jaw 289 carried by lever 299 pivotally mounted on stud 300 supported by a suitable bracket (not shown). A spring 291 is secured to pin 292 of jaw 288 and pin 293 on jaw 289 and tends to hold the jaws closed. Jaw 288 is moved into and out of gripping relationship with jaw 289 by means of a lever 282 arranged to engage cam portion 285 of jaw 288 so that the jaws are open to receive thread when located in the position shown in Figure 2 and discharge the same when by movement of lever 299 the jaws are positioned adjacent trap 311. The up and down movements of jaws 288, 289 and operation of lever 282 are controlled by means of cams (not shown) in the same manner as disclosed in the above mentioned copending Johnson application. Since the gripper forms no specific part of this invention further showing and description is deemed unnecessary.

As shown in Figure 1, a slack former and looper 181 mounted on an arm (not shown) moves relatively to the needle and upper needle bar to pull a small quantity of the thread back through the work, guide it, and prevent formation of poor stitches. In a manner similar to that shown in the above referred to application, looper 181 and a coacting member (not shown) operate in timed relation with the upper needle bar and needle for disposing the thread relative to the needle. Finger 182 of looper 181 engages the front thread F of the loop and pulls some of the thread back through slot 314 while the coacting finger in a manner similar to that described in said application moves into engagement with the other portion of the loop alongside the needle, and moves it out of the path of the needle, while at the same time the tension on the thread, passing through the eye of the needle, is lessened. When looper 181 starts its retreating movement, needle bar 63 descends and in so doing the extension of an actuator member (not shown) secured to member 63 engages the curved portion of the finger (not shown) causing the same to be returned to its starting position. The jaws 288 and 289 start descending with the descent of needle bar 63 and are returned to their starting position. A tension finger (not shown) disclosed in the above mentioned application, engages the thread and moves it out of the path of the needle 81 as it descends to form its stitch and be transferred to the opposite needle bar. Before each transfer of the needle, a suitable work feed mechanism (not shown) advances the work one stitch length.

Referring to Figures 1 and 2, a cam actuated brush 320 serves as a drag for the free end of the thread to control the movement from the drum and also to prevent any whipping or tendency to tangle as it is being pulled from the drum. The brush retains its active position as shown during the greater portion of the cycle of the shaft 205. The brush 320 is carried on the upper end of a lever 321, loosely mounted on a stud 322 supported by a wall of drum member 308, the opposite end of lever 321 being provided with a cam follower 323 engaging a cam 324 mounted on shaft 205. A spring 325 having one end attached to a stud anchored in member 308 and its other end connecting to a stud in lever 321, is provided to hold the cam follower 323 in engagement with its cam. In its operation the brush stays open until looper 181 begins to move forward, say two-thirds of its stroke, in order to pull up slack, but in order to prevent over-

run, the brush moves up to engage the thread being pulled and stays on from that time until the looper 181 completes its full slack pulling movement and the thread puller 202 has pulled the loose end of the thread through the work and disposed it on the drum. At the time of transferring the needle from the lower to the upper needle bar, the high portion of cam 328 engages cam follower 323 and moves the brush to its dotted position, the brush retains this position also for a part of the movement of the looper 181 and its coacting finger (not shown) as set forth above.

The drum 224 is partly surrounded by a tape 330 (Figure 1) which serves to maintain the thread in orderly fashion and also to prevent whipping of the thread as it is placed around the drum by the puller 202. This tape, at one end, is clamped between two plates 331, the lower one receiving one end of a tension spring 332 connecting with an arm 333 extending from a lug 334 of member 309, its other end being guided over rollers 335 suitably supported by a bracket of the machine and led over a segment 336 loosely mounted on a stud 337 carried by a bracket 338 attached to pedestal 33. The end of the tape is clamped between a plate 339 and the end wall of segment 336, which is equipped with a post 340 receiving one end of a spring 341 connecting to a post 342 anchored in bracket 338, said spring tending to yieldingly hold the tape against the drum.

As the thread puller 202 positions the thread around the drum 224 and if the tail end of the loose thread should remain on the shelf 307 on its return travel to be pulled through the work, the thread will be guided into the channel 343 (Figure 3) of the drum by means of guide members or shoulders 344 (Figures 1 and 4) provided in member 309. In this manner the free returning end of the thread will be guided out of the path of the oncoming thread being advanced by the puller, which might otherwise be pulled over it. Member 308 is provided with an undercut thread trap or guide portion 345 (Figure 3) which tends to keep the thread from flying out of the channel 343.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a sewing machine of the type described, having a pair of opposed needle bars for projecting a needle and a thread having a loose and a fixed end back and forth through material to be sewed, thread receiving drum mechanism located adjacent one of said bars, said mechanism comprising a ledge, a thread puller coacting with said mechanism for disposing the loose end of said thread upon said ledge, and a thread guide forming a part of said drum mechanism having an inclined face positioned above said ledge constructed and arranged to assist in the proper handling of said thread during the action of said puller.

2. In a sewing machine of the type having a pair of opposed needle bars for projecting a needle and a thread having a loose end back and forth through the work, a thread receiving drum located adjacent one of said bars comprising a substantially cylindrical member having a thread

receiving ledge formed thereon, an undercut thread guide located beneath said ledge, a vertical flanged element spaced from said member and provided with a substantially vertical elongated thread receiving slot constructed and arranged to receive thread, and means for moving said thread from said ledge to said slot.

3. In a sewing machine having a pair of opposed needle bars for projecting a thread and a needle through work to be sewed, a thread puller for pulling the loose end of said thread through said work, a thread receiving mechanism positioned to receive thread pulled by said puller comprising a pair of spaced members having laterally extending flanges, said flanges being spaced from each other, each of said flanges being constructed and arranged to receive a portion of the thread as it is pulled by said puller, and an undercut guide portion formed on one of said members for preventing said thread from moving upwardly from its thread receiving position.

4. Thread disposing mechanism for a sewing machine of the type described including, a thread receiving surface, means for disposing said thread about said surface, a substantially L-shaped receiving and guiding member having a substantially vertical circumferential flange and a lateral circumferential flange associated with said surface, a substantially vertical slot formed in said vertical flange of said member, a device spaced from and cooperating with said lateral circumferential flange of said member to form a thread guide for guiding thread from said surface into said vertical slot, and means for tensioning said thread during its movement.

5. A thread receiving drum comprising a member provided with a thread receiving surface, a second member spaced from said first and provided with a vertical flange, a substantially vertical elongated slot formed in said vertical flange, and a lateral flange formed in said second member constructed and arranged to receive thread displaced laterally from said surface and guide said thread towards said slot.

6. In a thread disposing mechanism for a sewing machine, a substantially cylindrical thread receiving and disposing drum comprising a thread receiving surface and a thread guide, and a thread disposing member associated with said surface, said member consisting of a lateral flange portion provided with a circumferential thread groove and a tapered thread guiding face adjacent to and above said thread receiving surface, and a guiding face on the underside of said member for guiding thread positioned on said receiving surface laterally therefrom.

7. In a sewing machine having a pair of opposed needle bars for projecting a needle with a thread having a fixed and a loose end back and forth through work to be sewed, thread receiving mechanism positioned adjacent one of said bars, said mechanism including a thread receiving surface, a thread drag positioned proximate said bar and surface, and means for moving said drag in timed relation to the movement of said bars into and out of thread engaging position.

8. In a sewing machine having a pair of opposed needle bars for projecting a needle with a thread having a fixed and a loose end back and forth through work to be sewed, a thread receiving surface extending from each side of one of said bars, a thread brake positioned adjacent one end of said surface, said brake comprising a lever, a brush mounted on said lever and projecting

towards said surface, and means for moving said brush to and from said surface.

9. In a sewing machine having a pair of opposed needle bars for moving a needle with a thread having a loose and a fixed end back and forth through work to be sewed, a split, substantially cylindrical thread receiving drum extending from opposite sides of one of said bars, a thread brake located between one of said bars and said drum, and means operating in timed relation to the movement of said bars for moving said brake into engagement with said thread.

10. In a sewing machine of the type described having a pair of opposed needle bars for projecting a needle and a thread provided with a fixed and a loose end back and forth through material to be sewed, a thread receiving mechanism located adjacent one of said bars, a thread puller for pulling the loose end of said thread through said material and depositing it on said mechanism, said thread puller being provided with a longitudinal groove on its lower face, a guide positioned adjacent said mechanism and arranged to coact with said groove for guiding the thread pulled by said puller onto said mechanism.

11. A thread pulling device for a sewing machine comprising an elongated head having an upper and a lower face forming a tapered thread engaging point and an elongated groove in said lower face, a supporting member mounting said head for movement into and out of engagement with a thread to be pulled, and a thread guide on said supporting member constructed and arranged to coact with said groove in said head during the thread pulling movement of said head.

12. In a sewing machine, having a pair of opposed needle bars for projecting a needle

threaded with a thread having a loose and a fixed end through work to be sewed, thread receiving mechanism positioned adjacent one of said bars, said mechanism comprising a stationary drum provided with a lateral flange having a thread receiving surface, a thread guide located below said surface, and a transverse guide member located below and spaced from said flange and forming therewith a guide slot for controlling the lateral movement of said thread from said thread guide into said slot.

13. Thread receiving mechanism for a sewing machine comprising a drum, spaced connected members forming said drum, one of said members being provided with a thread receiving surface, and a undercut thread trap guide, the other of said members comprising a substantially L-shaped cylindrical member with a substantially vertical flange and a circumferentially extending lateral flange, a thread guiding surface formed on said lateral flange, and guide means mounted on said L-shaped member and spaced from said lateral flange coacting with said surface for guiding thread laterally from said thread receiving surface.

14. Thread disposing mechanism for a sewing machine of the type described including, a thread receiving surface, means for disposing said thread about said surface, a substantially L-shaped thread receiving and guiding member provided with a substantially vertical flange and a lateral flange associated with said surface, said member having a generally vertical slot formed in said vertical flange, and a device spaced from and 30 cooperating with the lateral flange of said member to form a thread guide therebeneath for guiding thread from said surface into said vertical slot.

MATHIAS PEDERSEN.
